UNITED STATES PATENT OFFICE.

EDWARD B. HEINOLD, OF ANDERSON, INDIANA.

STARCHING-MACHINE.

SPECIFICATION forming part of Letters Patent No. 712,065, dated October 28, 1902.

Application filed January 15, 1901. Serial No. 43,327. (No model.)

To all whom it may concern:

Be it known that I, EDWARD B. HEINOLD, a citizen of the United States, residing at Anderson, in the county of Madison and State 5 of Indiana, have invented certain new and useful Improvements in Starching-Machines, of which the following is a specification.

This invention relates to improvements in machines for starching collars, cuffs, and the 10 like articles made of textile fabrics, said articles being hereinafter referred to as "goods;" and the object of the invention is to provide a machine of comparatively few parts, of low cost to construct, simple in its operation, and 15 durable, to thoroughly and quickly incorporate the starch into the goods.

I accomplish the objects of the invention by the mechanism illustrated in the accompanying drawings, in which—

20 Figure 1 is a plan view of a starching-machine embodying my invention; Fig. 2, an elevation of same, showing the legs broken away. Fig. 3 is a vertical central longitudinal section on the dotted line 3 3 of Fig. 4; 25 Fig. 4, a transverse section on the line 4 4 of Fig. 3; Fig. 5, a detail showing the woven-wire drum-covering construction; Fig. 6, a detail of the small roller adjustable bearing; Fig. 7, a detail of the side of the tank, showing 30 the manner of securing the roller-frame suspension-rods; Fig. 8, a side elevation of one of the rollers, showing the end grooves and string or cord therein to hold the roller-cover in place; Fig. 9, a detail on a larger 35 scale, showing one of the drums and the two rollers and belt working therewith; and Fig. 10, a detail view similar to a portion of Fig. 9, on an enlarged scale.

Like characters of reference indicate like 40 parts throughout the several views of the drawings.

1 represents a starch-tank suspended from the walls, on the inside of which is the operative mechanism of my invention, hereinafter 45 to be described. Underlying and adjacent to the bottom of the tank 1 is the steam-chamber 2, which receives steam through a pipe at 3, Fig. 2, to keep the starch in the tank 1 suitably heated. An outlet 4 for the 50 ready removal of the starch is provided through the side of the tank, and an outlet 5

is provided in the bottom of the steam-chest for the discharge of the steam.

6 is a frame comprising two trussed side pieces which are united by the end rods 7 7 55 and middle rods 8 and 9. The lower middle rod 8 and the rods 7 7 project beyond the sides of the frame a suitable distance to contact with the sides of the starch-tank 1 and support the frame in the position shown in 60 Figs. 3 and 4. To prevent longitudinal movement of the frame on the sides of the tank, I provide notches 10, Figs. 2 and 7, into which the ends of the rods take, and to prevent longitudinal movement of the end rods in 65 the slots I notch the upper sides of the rod ends and pass a pin through said notch and through the walls of the tank in the manner shown in Fig. 7, in which 11 represents the pin. Supported by this frame 6 and mounted 70 between the sides thereof are the cylinders or drums 12 and 13 and the four smaller rollers 14, 15, 16, and 17, and passing over and under the four last-mentioned rollers and under the said drums 12 and 13 is the 75 continuous belt 18. The pressure between the two drums 12 and 13 and the four rollers 14, 15, 16, and 17 through the belt 18 is sufficient to cause the said rollers to revolve by 80 the rotation of the drums, thereby causing 80 the belt to travel, causing the goods fed in between drum 12 and roller 14 to be carried through the machine and discharged between drum 13 and roller 17. Drum 12 is mounted on shaft 18 and drum 13 on shaft 19, and the 85 projected end of shafts 18 and 19 are provided with the toothed wheels 20 and 21, which engage worms 22 and 23 on shaft 24, situated alongside of the starch-tank and supported on brackets therefrom. This shaft 90 has the tight belt-pulley 25, which is connected by belt with any suitable source of power, and it also has the loose pulley 26, upon which the belt will be shifted to throw the mechanism out of action. The quantity 95 of starch maintained in the starch-tank is sufficient to cover the two lower rollers 15 and 16 and to cover the lower portions of drums 12 and 13 and rollers 14 and 17. The drum 12 is hollow, so that the starch is free 100 to circulate through it, and its periphery is a woven-wire construction with meshes form-

ing perforations for the passage of starch therethrough. The construction of drum 12 is as follows: Rings 26, supported from hubs by suitable spiders, are connected by a series 5 of rods 27, and wound around the cylinder thus formed in an open spiral is the heavy wire 28, forming a strong foundation, upon which is laid the wire-cloth 29, and upon this cloth 29 is wrapped the cloth 30, made of much 10 finer wire woven with much closer meshes. The belt 18 coming out of the body of starch in the tank is thoroughly covered with starch, and the belt being held closely against the bottom of the drum 12 by a proper adjustment 15 of the rollers 14 and 15 causes the starch carried by it to be driven through the goods by the pressure of the belt against the open-work surface of the drum as the goods are carried under the drum by the progress of 20 the belt. The open-work resistance provided by the periphery of the cylinder is reduced to mere lines of contact along the wires of the outside cloth, so that the forcing of the starch through the goods is not obstructed 25 by any solid surface on the periphery of the cylinder or drum. This peculiar construction constitutes one of the leading features of my invention and enables me to apply the starch in a particularly uniform and even manner. 30 The goods thoroughly saturated with starch issue from between drum 12 and roller 15 and are carried by the belt from roller 15 to roller 16 and thence between drum 13 and rollers 16 and 17, by which the excess of starch 35 is pressed out by said drum and rollers. The peripheries of the drum 13 and rollers 14, 15, 16, and 17 are of wood covered with silence-cloth, canton-flannel, or other material having a loose pile.

40 The sides of the frame 6, at the ends thereof, are provided with the rectangular frames 31, (see Fig. 6), having the movable bar 32 with guide-pins 33, surrounded by springs 34 to press the bar 32 against the boxes 35, in 45 which runs the shafts of the rollers 14 and 17. The construction affords a yielding pressure of the rollers against their respective drums and permits thick portions of goods to pass between without clogging the machine. The 50 boxes 35 have an adjustment in the space between the bar 32 and the frame 31, controlled by the bolt 36, which passes through a threaded opening in the frame and has a swivel or ball-and-socket connection with 55 the box, the direction being such that when the boxes are moved upwardly the rollers on the shafts supported by said boxes will be drawn closer toward their adjacent drum, but when moved in a downward direction said 60 rollers will be separated from said drums. The construction by which an upward movement of the journal-box will tighten the roller against the drum and loosen it when moved in a downward direction is best illustrated in 65 Fig. 9, in which xx represents a radial line of the drum, yy a line tangent to both roller and drum, and zz a line parallel with the

sides of the way in which the journal-box is adjustably mounted and oblique to the radial line xx . This line zz shows the direction of 70 movement of the roller when it is adjusted and shows clearly that an upward adjustment tightens the roller against the drum, while a downward adjustment loosens it. As the boxes at each end of the roller-shafts are independently adjustable, one can be moved without disturbing the other, thereby enabling any looseness in one side of the belt to be taken up in order to cause the belt to run even. 80

The side members of the frame 6 have hangers 37, terminating in rectangular runs 38 for the boxes 39 for shafts of rollers 15 and 16. The boxes are set up with set-screws 40, having tapering ends, which enter springs between the bolt ends and boxes to afford a yielding resistance. 85

The amount of starch given to the goods will be determined by the pressure of the rollers 14, 15, 16, and 17 against the drums 12 90 and 13, and this is controlled by the screw-bolts 36 and 40. The line of contact between roller 15 and drum 12 is made low on the latter to prevent the goods from being carried around on drum 12, as would be the case were 95 the roller set higher up—as, for example, as high as it appears in the case of roller 17. In the latter case it is desired that the goods adhere to the large drum instead of following around roller 17, for the reason that they can 100 the more readily be picked off of the larger surface of the drum 13.

41 is a belt-tightener consisting of a roller supported by the vertical longitudinally-adjustable rods 42. 105

The rollers 14, 15, 16, and 17 have annular grooves g near their ends for two purposes—first, to form a hold for a string to be wrapped around the roller to prevent longitudinal slipping of the roller-cover, and, second, to receive ropes 42^a, fastened near the edges of the belt on the side of latter which contacts with said rollers for the purpose of keeping the belt from running off of said rollers. 110

It will be recalled that frame 6 is suspended 115 in the starch-tank by rods 77 and 8 and that end rods 77 are secured by cross-pins. When it is desired to raise drum 12 or 13 into position for easy access for the purpose of cleaning or repairs, its adjacent end rod is released 120 by the removal of the pins which hold it. Then said end is lifted high enough to allow the adjustable supports 43 to be introduced under ends of rod 8. The supports 43 are pivotally secured at one of their ends to the 125 sides of the starch-tank and have forks at the other end to receive the ends of the rod 8. The elevated position of the frame and drum is shown by dotted lines in Fig. 2. Both ends of the frame, with its accompanying drum, can 130 be elevated in the manner just described.

44 44 are removable tables placed at each end of the starch-box. They have under side hooks 45 to hook over the end rods 77 and

braces 46 to support the outer edges of the tables.

Adjustably secured to the table at the discharge end of the machine is the stripping-plate 47, which removes from the roller 17 whatever goods may cling to it instead of following the drum 13, and to guard against goods clinging to the drum 12 I provide the stripper 48.

10 Instead of the shaft with double worm-gear to drive the two drums one drum might be connected with the power and its shaft belted to the shaft of its mate, and other modifications in this and other parts of the machine—such, for example, as dispensing with the drum 13, which while not as satisfactory in point of quality and quantity of work produced provides a much cheaper construction as to cost of manufacture.

20 Having thus fully described my invention, what I claim as new, and wish to secure by Letters Patent, is—

1. In a starching-machine, a cylinder comprising a plurality of rings supported from a hub, rods connecting the rings approximately parallel with the axis of rotation of the cylinder, wires laid thereon around the cylinder in curves, a coarse wire-cloth laid on the wires and a cloth of finer and closer woven wires 30 laid on the first-mentioned cloth, substantially as described and shown.

2. In a starching-machine, a cylinder or drum having an outside periphery of wire-cloth an adjacent underlying and supporting layer of heavier wire-cloth and an open frame or support for said cloth layers, substantially as described and shown.

3. In a starching-machine, a cylinder or drum having a woven-wire periphery built up of several layers of wire-cloth of varying fineness of wire and mesh, and means for passing goods under the cylinder and for regulating the quantity of starch given thereto consisting of a plurality of rollers, a belt connecting the rollers and held against a portion

of the cylinder or drum by said rollers and a starch-tank in which said mechanism is suspended, substantially as described and shown.

4. In a starching-machine, a tank, a cylinder or drum having a woven-wire periphery and a hollow interior, a second drum having a solid surface covered with a soft material, rollers and a belt connecting the rollers and held in contact with a portion of said drums by said rollers, substantially as described and 55 shown.

5. In a starching-machine, a tank, a frame removably secured to the sides of said tank, a drum supported by said frame having a woven-wire periphery, a second drum supported by said frame having a solid periphery, a pair of rollers for each drum, a belt connecting the rollers and held by said rollers against a portion of said drums and means for imparting an equal motion to said drums, 65 substantially as described and shown.

6. The combination, with a starch-tank having vertically-slotted sides and removable pins crossing said slots, of a double truss forming the bearing-frame for the drums and 70 rollers of the machine, each truss having three lateral outside projections or rod ends, one at either end of the truss and one intermediate of said end projections, said frame being suspended in the starch-tank by placing the rod 75 projections at the ends of the frame in the slots, below the removable pins crossing said slots, and an adjustable support hinged to the tank and adapted to be elevated to engage the middle rod ends and support the frame 80 when the latter is raised at its ends, substantially as described and shown.

In witness whereof I have hereunto set my hand and seal, at Indianapolis, Indiana, this 3d day of January, A. D. 1901.

EDWARD B. HEINOLD. [L. S.]
